ORA B. GILBERT, OF FORT LEAVENWORTH, KANSAS, ASSIGNOR OF ONE-HALF TO
G. FRIEDRICH W. KNUTH, OF FORT LEAVENWORTH, KANSAS.

WINDOW-SASH-OPERATING DEVICE.

1,250,445.

Specification of Letters Patent. Patented Dec. 18, 1917.

Application filed April 24, 1917. Serial No. 164,100.

To all whom it may concern:

Be it known that I, ORA B. GILBERT, a citizen of the United States, residing at Fort Leavenworth, in the county of Leavenworth and State of Kansas, have invented certain new and useful Improvements in Window-Sash-Operating Devices, of which the following is a specification.

My invention relates to window sash operating devices, and my object is to provide a simple and efficient device of this character whereby the upper sash can be raised and lowered without the operator touching said sash. By the use of my device, the upper sash can be operated without having to first raise the lower sash in order to gain access to the meeting rail of the upper sash for the purpose of raising or lowering the latter.

In order that the invention may be fully understood, reference will now be made to the accompanying drawings, in which:

Figure 1 is a broken front elevation of a window frame with its sashes equipped with the invention.

Fig. 2 is an enlarged broken vertical section on line II of Fig. 3.

Fig. 3 is a plan view.

Fig. 4 is an irregular broken vertical section on line IV of Fig. 2, with the lower sash sash and its respective roller added.

Fig. 5 is a detail perspective view of a bracket for supporting the right end of the rollers.

Fig. 6 is a detail perspective view of a bracket for supporting the left end of the rollers.

Fig. 7 is an elevation of a cam roller and its bracket, employed in carrying out the invention.

Referring now in detail to the various parts, A designates a window frame of ordinary construction, excepting that the four sheaves usually placed at the upper inner sides of said frame for the sash cords to run over are dispensed with and my two rollers hereinafter described are employed instead. The window frame A is provided with the usual upper and lower slidable sashes B and C, respectively.

The upper sash B is normally held in raised position by sash cords 1 and 2 and sash weights 3 and 4. The sash weight 4 is, preferably, heavier than the weight 3 for a purpose which will hereinafter appear.

The sash weights 3 and 4 operate in the usual pockets in opposite sides of the window frame A. The cords 1 and 2 are wrapped around a roller 6 and attached at their upper ends to the upper sash B by any suitable means such as screw eyes 7, while their lower ends are attached to the weights 3 and 4, respectively. Slots 10 are formed in the upper portion of the window frame A for the passage of the cords 1 and 2 and also to receive the screw eyes 7 when the sash B is raised to the end of its upward movement.

The ends of the roller 6 are journaled in brackets 12 and 13, which latter has two cheeks 14 and 15. The cheek 14 has a circular opening 17 to allow the adjacent end of the roller 6 to extend therethrough and the cheek 15 has a small hole 18 in which the trunnion 19 of the roller 6 is journaled. The brackets 12 and 13 have extensions 20 and 21, respectively, at their lower ends which are driven into the window frame A and thus reliably hold said brackets in position.

23 designates an actuating cord for pulling the sash B downwardly. Said cord 23 is wound around the roller 6 and has its inner end attached either to the lower end of the sash cord 2 or the upper end of the weight 4, while its outer portion runs over a cam pulley 25 mounted in a bracket 26 secured to the inner face of the window frame A. The lower end of the actuating cord 23, is preferably, attached to an ornamental tassel 27 which affords a convenient grip when operating said cord 23.

By making the weight 4 larger than the weight 3 it not only coacts with said weight 3 in overbalancing the sash B to normally hold it in raised position, but also holds the actuating cord 23 taut and prevents its coils from getting loose on the roller 6, while the plate 14 through which the right end of the roller 6 extends prevents said coils from shifting to the right far enough to get caught between the right end of said roller 6 and the cheek 15 of the bracket 13.

The counterweights 28 for the lower sash C, are only heavy enough to hold said sash at any point to which it may be raised or lowered by hand in the usual way. Said counterweights 28 are secured to the lower ends of sash cords 30, extending upward to a roller 32 around which they are wound, and thence downwardly through slots 31 and are attached to the top of said sash C by 110

suitable means such as screw eyes 33. The roller 32 parallels the roller 6, and like the same is journaled at its ends in the brackets 12 and 13.

5 In practice the lower sash C is raised and lowered in the usual manner, but the upper sash B is lowered by pulling downward upon the outer portion of the actuating cord 23, or its tassel 27. This operation rotates 10 the roller 6 and through the intermediacy of the cords 1 and 2 raises the weights 3 and 4 and permits the upper sash B to descend. After the upper sash B has descended to the 15 desired point it is held at such point by the cam roller 25 which coacts with its bracket 26 in gripping the actuating cord 23 and preventing it from moving upwardly. To raise the sash it is only necessary to release 20 the actuating cord 23 from between the roller 25 and its bracket 26, whereupon the weights 3 and 4, being heavier than the sash, raise the same through the intermediacy of the cables 1 and 2.

While my device can be used to advantage 25 on average size sashes such as are used in residences, it is of especial advantage when applied to large windows such as are used in office buildings and the upper sashes of which under ordinary circumstances are difficult 30 to gain access to, owing to their height, for the purpose of raising or lowering said sashes.

From the foregoing it is apparent that I 35 have produced a device whereby upper sashes may be easily and quickly operated and while I have shown and described the preferred form of my invention, I reserve the right to make such changes in the construction, combination and arrangement of parts 40 as properly fall within the spirit and scope of the claims.

Having thus described my invention, what

I claim and desire to secure by Letters Patent, is:

1. In combination with a window frame 45 and a slideable sash thereto, a roller journaled at the upper portion of said frame, overbalancing means to normally hold the sash in raised position, cables wrapped around the roller and attached at their ends to said overbalancing means and the sash, an actuating cord wrapped around the roller and attached at its inner end to one of the cables and having its opposite end depending adjacent the inner side of the window frame, the overbalancing means of the last named cable exerting greater tension than the overbalancing means of the other cable so as to hold the cord taut, a cam roller over which the outer portion of the actuating cable runs, and a 50 bracket secured to the window frame to carry said cam roller and coact therewith in securing the actuating cable in position to hold the sash open.

2. In combination with a window frame 65 having an opening in a side thereof and having a slideable sash, a roller journaled in the frame top, overbalancing means, cables wrapped around the roller and connected to said overbalancing means and to the sash, 70 an actuating cord engaged with the roller between the cord ends to rotate the roller and having one end connected to one of the cables and having its other end extending through said opening in the side of the window frame and extending on the inner face 75 of the latter, and means to hold said cord against movement.

In testimony whereof I affix my signature, in the presence of two witnesses.

ORA B. GILBERT.

Witnesses:

LAURENCE A. CARTER,
JAMES B. ROUSSEAU.
